UNITED STATES PATENT OFFICE.

ALFRED LEKBERG, OF PORTLAND, OREGON.

FIRE-KINDLER.

1,218,284.

Specification of Letters Patent.

Patented Mar. 6, 1917.

Application filed May 27, 1916. Serial No. 100,198.

To all whom it may concern:

Be it known that I, ALFRED LEKBERG, a citizen of the United States of America, residing at Portland, in the county of Multnomah, in the State of Oregon, have invented a certain new and useful Fire-Kindler, of which the following is a specification, reference being had to the accompanying drawing.

10 My invention relates to fire kindlers and has for its object the production of an economical, convenient, and effective device for utilizing gas as a means for kindling a coal or wood fire. The gas necessary to operate 15 my device may be obtained from any convenient source, for example, the service pipe of any local gas supply system.

The idea in its broadest sense of utilizing a gas torch as a fire kindler so far from being novel is public property. My invention comprehends improvements in devices of the above general description.

What constitutes my invention will be hereinafter described in detail and succinctly set forth in the appended claims.

25 In the accompanying drawing,

Figure I is a side elevation of my invention complete in preferred form of embodiment, as applied to a stove which is partially 30 shown in vertical section transverse to the fire box.

Fig. II is a plan view of the adjustable stop piece detached.

Fig. III is a transverse section of Fig. I.

35 Fig. IV is another transverse section of Fig. I.

Fig. V is a central longitudinal section of the butt end of the device shown in Fig. I.

Fig. VI shows the rear portion of the 40 coiled grip shown complete in Fig. I, the view being taken at right angles to that given in Fig. I.

Referring to the numerals on the drawing, 1 indicates a metallic, preferably, iron, 45 tube, that is closed at one end as indicated at 2 in Fig. I and is joined, as by a threaded joint 3 (Fig. V) to a nipple 4 adapted to slip into the end of hose 5, by which it is brought into convenient operative relation- 50 ship to a gas service pipe or other source of gas supply, not illustrated.

The tube 1 is provided with discharge 55 apertures 6 near its closed end 2, and is, as by the aid of a gas nozzle 7 projecting into it from the nipple 4 in proximity to air

supply apertures 8 in the tube, preferably made to constitute a Bunsen burner. A slip collar 10 fitting snugly about the tube 1 adjacent to the apertures 8 affords suitable means for regulating the air supply to the 60 interior of the tube after the manner common to burners of the Bunsen type.

My invention consists in providing about the butt of the tube 1 a cool grip 11 preferably made of wire coiled about the tube. 65 The coil of the wire is such as to snugly secure the grip 11 in place about the tube, and also afford a ring 12 by which the device may be hung up when not in use.

The diameter of the grip is sufficiently 70 greater than that of the tube 1 to insure it against becoming overheated in service and also to afford a protective covering to the collar 10 as well as to the stop piece 14 with which the tube is preferably provided. 75

The stop piece preferably consists of a plate extending endwise of the tube 1 for a portion of its length. It is provided at its end toward the closed end of the tube 1 with a hook or arm 15, and is provided with 80 a series of holes 16 through any one of which a screw 17 may enter and engage a threaded aperture provided for it in said tube.

The office of the hook or arm 15 is to engage a stove frame 18 and hold the tube in place within the stove while it is doing the work of kindling the combustibles. By aid of the adjustability of the stop piece 14 the hook or arm may be moved toward or from 90 the closed end 2 of the tube 1 and fixed in the position to which it is adjusted so as to bring its apertures 6, when in use, substantially in the middle of the pile of combustibles to be kindled. 95

The operation of my device may be briefly described as follows.

After having been connected by the hose 5 to a source of gas supply and the hook 15 adjusted and fixed to suit the stove it is intended to serve, the device is ready for instant service at any time. It is only necessary to turn a gas cock, light the gas, thrust the closed end 2 of the tube 1 into the midst of the combustibles, and hang the hook 15 in place upon any convenient edge of the stove. The device may be with perfect impunity left in place until the fire is well kindled, when, at the convenience of the operator it may be withdrawn, the gas 110

turned off, and the device hung out of the way on its ring 12.

What I claim is:

1. A fire kindler comprising the combination of a tube provided at one end with a discharge aperture, means for securing the butt end of the tube to a source of gas supply, a cool grip surrounding the butt end of the tube, and an adjustable stop piece 10 on the tube, consisting of a plate extending endwise of the tube and provided with a hook to hold the tube in place while in service.
2. A fire kindler comprising the combination of a Bunsen burner tube provided at one end with a discharge aperture, means for securing the butt end of the tube to a source of gas supply, and a cool grip surrounding the butt end of the tube and affording a protective covering to the air supply 15 apertures with which the Bunsen tube is provided.
3. A fire kindler comprising the combination of a Bunsen burner tube provided at one end with a discharge aperture, means for securing the butt end of the tube to a source of gas supply, and a cool grip surrounding the butt end of the tube and affording a protective covering to the air supply 20 apertures with which the Bunsen tube is provided, said grip consisting of a coil of wire and a ring formed of a coil of the wire constituting the grip.

In testimony whereof, I have hereunto set my hand in the presence of two subscribing witnesses.

ALFRED LEKBERG.
Witnesses:

HOWARD O. ROGERS,
MABEL NEVILLE.
